UNITED STATES PATENT OFFICE.

WILLIAM T. PRINGLE, OF NEW YORK, N. Y.

MACHINE FOR CUTTING THE CORNERS OF BOOKS, CARDS, AND PAPER.

SPECIFICATION forming part of Letters Patent No. 224,475, dated February 10, 1880.

Application filed October 20, 1879.

To all whom it may concern:

Be it known that I, WILLIAM T. PRINGLE, of the city, county, and State of New York, have invented a new and useful Improvement 5 in Machines for Cutting the Corners of Books, Cards, and Paper, of which the following is a specification.

Figure 1 is a plan view of the machine. Fig. 2 is a side elevation, partly in section. 10 Fig. 3 is an end elevation. Fig. 4 is a front elevation of the knife-holder. Fig. 5 is a side elevation of the knife-holder.

The object of this invention is to furnish machines for cutting the corners of cards, 15 books, albums, paper, and other substances.

A represents the table of the machine, which is attached to a frame, B, of convenient height. To the rear part of the table A are attached two parallel uprights, C, the adjacent sides of which are grooved to serve as 20 ways for the knife-holder D. To the lower end of the holder D is bolted or otherwise secured the knife E. The knife E may be concaved, as shown in Fig. 4, to cut a rounded 25 corner, or convexed to cut a concaved corner, or straight to cut a straight corner, as may be required.

To the upper end of the holder D is pivoted the lower end of a bar or link, F, the upper 30 end of which is pivoted to the end of the curved arm G. The arm G is rigidly attached to the shaft H, which rocks in bearings in the upper ends of forwardly projecting arms I, formed upon or attached to the forward side 35 of the upper ends of the uprights C. To one end of the shaft H is attached the end of the lever J, by means of which the shaft H is rocked to raise and lower the knife-holder and knife D E.

40 To the table A are attached, by their lower edges, two guide boards or plates, K, at an angle of forty-five degrees (45°) with the table A, so that their adjacent ends, if extended, would meet at a right angle. A sufficient 45 space is left between the adjacent ends of the guide-boards K for the corner of a pile of books or cards to project sufficiently to be cut by the knife E as it is forced down by the movement of the lever J.

The pile of books or cards is pressed down 50 and held while being cut by the bar L, which crosses the upper edges of the adjacent ends of the guide-boards K, and the middle part of which is made thicker, so as to project downward between the said guide-boards K, as 55 shown in Fig. 3.

To the end parts of the presser-bar L are attached the upper ends of two rods, M, which pass down through holes in the table A, and their lower ends are attached to the foot-lever 60 or treadle N. The inner end of the treadle N is hinged to the frame B, or to a bar attached to the said frame, and its outer end projects into such a position that it may be reached and operated by the operator with his foot to 65 draw down the presser-bar L and hold the pile of books or cards firmly while being cut. To the outer part of the treadle N is attached the end of a cord, O, which passes through guide-eyes P, or over guide-pulleys attached 70 to the under side of the table A. To the other end of the cord O is attached a weight, Q, sufficient to raise the treadle N and bar L when the operator withdraws his foot from the treadle N, so that the pile of books or 75 cards can be inserted and removed.

In the table A, at the rear side of the knife E, is formed an inclined chute or spout, R, so that the scraps when cut off may slide to the floor or into a receiver placed beneath the 80 table A.

Having thus described my invention, I claim as new and desire to secure by Letters Patent—

1. The combination of the table, the knife 85 E, the guide-boards K, and the pressure-bar L, made thickest in the middle, as and for the purpose set forth.

2. The combination, with the pressure-bar L, of the rods M, the treadle N, the cord O, the 90 eyes P, and the weight Q, as and for the purpose specified.

WILLIAM T. PRINGLE.
